UNITED STATES PATENT OFFICE

2,414,227

SEWING MACHINE

Charles F. Goforth, Wichita, Kans.

Application June 4, 1942, Serial No. 445,788

1 Claim. (Cl. 112—184)

1

This invention relates to sewing machine construction, an important object of the invention being to provide a sewing machine including an oscillating member, constructed to operate in a horizontal plane and used in lieu of the usual well known loop taker.

Another object of the invention is to provide an oscillating thread-engaging member having oppositely disposed thread hooks, so arranged that regardless of the direction of the initial movement of the hand wheel of the sewing machine by the operator, one of the thread hooks will be in a position to pick up the loop in the thread, formed by the needle of the machine in passing through the material being sewed, and carry the loop to a position around the bobbin thread, in forming a stitch, thereby eliminating improperly formed stitches which usually occur by starting the hand wheel in the wrong direction.

With the foregoing and other objects in view which will appear as the description proceeds, the invention consists of certain novel details of construction and combinations of parts herein-after more fully described and pointed out in the claim, it being understood that changes may be made in the construction and arrangement of parts without departing from the spirit of the invention as claimed.

Referring to the drawings:

Figure 1 is a longitudinal sectional view through a sewing machine constructed in accordance with the invention.

Figure 2 is a bottom plan view thereof.

Figure 3 is a sectional view taken on line 3—3 of Figure 1.

Figure 4 is a sectional view taken on line 4—4 of Figure 1.

Figure 5 is a bottom plan view of the oscillating double hook member.

Figure 6 is an elevational view of the oscillating member and bobbin case mounted thereon.

Figure 7 is a vertical sectional view through the oscillating member and bobbin case.

Figure 8 is a view illustrating the initial position of the needle thread loop, with respect to the bobbin thread.

Figure 9 is an elevational view of the machine head cover plate.

Referring to the drawings in detail, the reference character 5 designates the support or table of the sewing machine, indicated generally by the reference character 6.

The reference character 7 designates the power shaft of the sewing machine which is operated

2

by a suitable belt not shown, moving over the pulley 8, mounted thereon.

In the head 9 of the sewing machine is located the usual vertically movable needle bar 10 that carries the needle 11. The power shaft 7 transmits movement to the needle bar 10, through the crank arm 10' mounted on one end of the power shaft, the crank arm being connected with the link 11', that in turn connects with the needle bar 10 through the collar 12' and stub shaft 13'.

Operating adjacent to the needle bar, is the presser-foot bar 12. On the lower end of the bar 12, is mounted the presser-foot 13 which operates with the feed mechanism of the machine in moving the material being sewed, through the machine. Operating between the arms of the member 14', is an eccentric 16, that is secured to one end of the power shaft 7, whereby rotary movement of the power shaft 7 is converted into reciprocatory movement of the needle bar 10 and take-up bar 56. Secured on the shaft 7 is a sleeve 14 on one end of which is mounted a pinion 15, the opposite end of the sleeve 14 carrying the disk 34 over which the eccentric 16, to be hereinafter more fully described, operates.

Adjustable bearings 17 and 18 extend into depressions formed in the hub 19 of the member 20, so that the member 20 may be rotated freely on the adjustable bearings. A gear indicated at 21 is formed at one end of the member 20 and meshes with the pinion 15, whereby rotary movement of the power shaft 7 is transmitted to the member 20. Formed in the periphery of the member 20, is a cam groove 22 into which the pin 23 extends, the pin 23 being carried at the upper end of the pivoted arm 24 which is supported at a point substantially intermediate its ends, by the mounting 25. The lower end of the arm 24 extends through an opening in the supporting table 5, and terminates at a point below the table 5 as clearly shown by Figure 1 of the drawings. Pivoted connected to the lower end of the arm 24, is a rack bar 26 that engages the segmental gear 27. This segmental gear 27 is secured to the tubular bearing member 28 that is secured to the shaft 30, the bearing member 29 being mounted in bearings seated in the bracket 28. The shaft extends from the center of the oscillating double-pointed hook member 31 which operates in a horizontal plane directly under the needle and presser-foot of the machine.

This double-pointed hook member 31 is of a novel construction, and embodies a disk-like

member formed of suitable sheet metal material, the peripheral edge thereof being turned upwardly and inwardly as clearly shown by Figure 5 of the drawings, providing a flange 32. A portion of the flange 32 is cut away providing spaced hooks 33 at the ends thereof, the hooks 33 being disposed in opposite directions with respect to each other, providing thread hooks that are designed to hook into loops formed in the thread, by the needle of the machine, in carrying the needle thread around the bobbin thread.

The flange 32 rests in the annular groove 32', formed in the periphery of the bobbin case 33' supporting the bobbin case on the hook member 31. A flange 34' forms a part of the bobbin case and has a cut-out portion 35' through which the needle of the machine extends in forming the stitch. In order that the bobbin case will be held against rotary movement, a pin 36' is provided and extends downwardly from the lower surface of the table 5, terminating at a point above the hook member 31. It will of course be understood that the double-pointed hooks and the operation of the same is such that regardless of the direction of oscillation in which the double-pointed hook is started, one of the hooks will pick up the thread from the needle and form the stitch.

It might be further stated that the construction of the cam groove 22, causes a movement of the pivoted arm 24 which in turn operates the rack bar 26 to oscillate the double-pointed hook member and cause the double-pointed hook member to cease oscillation for a predetermined period, prior to the starting movement of the member 31 in the reverse direction.

Mounted on the power shaft 7, to move therewith, is an eccentric, which embodies a disk 34 and eccentric band 35, the band 35 being secured to the upper end of the arm 36 mounted in one end of the sewing machine. The arm 36 is pivotally secured to the link 38, through the pin 37, the link 38 having an elongated opening, as clearly shown by Figure 4. This link 38 is pivotally mounted on the shaft 39' secured within the machine housing.

Mounted within the sewing machine, is an arm 38' on one end of which the roller 39 is mounted, the roller moving through the elongated opening, so that movement of the pivot arm 36, results in a relative movement of the arm 38'.

Thus it will be seen, that due to this construction, the position of the roller 39 within the elongated opening, may be adjusted longitudinally thereof, to vary the throw of the arm 38'.

The adjustment of the arm 38' with respect to the link 38, is accomplished by the operation of the lever 40', which is extended through an opening in the sewing machine, there being provided a link 41' connecting the lever 40' with the arm 38' so that as the lever is swung on its pivot, the roller 39 is moved longitudinally of the link 38.

This arm 38' has connection with the arm 42 that in turn is secured on the shaft 43 mounted under the sewing machine table.

This shaft 43 extends throughout the length of the sewing machine, and carries the feed bar operating mechanism 44 at one end thereof. Mounted directly under the sewing machine, is the feed bar 45 that has teeth 46 near the free end thereof, the teeth being adapted to cooperate with the presser-foot, in feeding material being sewed, under the needle.

One end of the bar 45 is forked at 45' and accommodates the pin 46', whereby the bar 45' is permitted to reciprocate under the table 5 of the machine.

This feed bar 45 includes an arm 49 extending upwardly towards the presser-foot 13, the serrated end 50 thereof cooperating with the presser-foot 13 in feeding material through the machine. Thus it will be seen that when the machine is in operation and the shaft 43 is rotated backwardly and forwardly substantially a quarter turn in each direction, the feed arm 49 is operated to feed the material through the machine. In order that the feed mechanism may be adjusted, the lever 40' may be operated to move the arm 38' to various positions within the elongated opening of the right-angled end portion of the arm 38, thereby adjusting the length of throw of the arm 38' with the result that the sewing machine may be adjusted for making a substantially long stitch as in basting. By moving lever 40' to the limit of its upward movement the feed is reversed, since the movement of the arm 38', shifts the roller to the opposite end of the elongated opening, or to the position as shown in dotted lines in Fig. 4 of the drawings, with the result that downward movement of arm 36 moves the arm 38' downwardly instead of upwardly, as would be the case when the roller 39 is positioned in the opposite end of the elongated opening.

The cover plate for the head of the sewing machine, is indicated by the reference character 51, and is formed with a notch 53 at one corner thereof, through which the top thread or thread 35 from the spool of the machine extends. The cover plate 51 also provides a support for the top thread-tensioning device which embodies a spring plate 52 secured to the cover plate 51, by means of the set screw 54. Hook 55 forms a part of the thread-tensioning device, under which the thread passes from the notch, the thread passing upwardly from the hook 55 and through the eye in the arm 56 which extends through an elongated opening in the cover plate. This arm 56 is formed with a pivoted end 56' which is normally held in an extended position by the spring 57' mounted adjacent to the pivot point between the pivoted end and arm 56. This pivoted end moves downwardly when the thread becomes exceptionally taut, thereby preventing breaking of the thread due to lack of resiliency at the point of contact between the thread and arm. From the arm 56, the thread passes downwardly to the needle.

From the foregoing it will be seen that due to the construction of the double-pointed hook 31, the hook will pick up the needle thread in forming the stitch, regardless of the direction of oscillation in which the hook is started, thereby insuring against an improper stitch. It will also be seen that by adjusting the lever 40', the length of the stitch may be regulated, to the end that long stitches may be made, as in basting, and by throwing the lever 40' from the top to the bottom it reverses the feed and vice versa.

On forming a stitch, the threaded needle passes downwardly through the material being sewed, and through the cut-out portion in the flange of the bobbin case, forming a loop A as shown by Fig. 8 of the drawings. The hook at one end of the cut-away portion of the member 31, depending on the direction of rotation of member 31, moves into the loop spreading the loop and, carrying the thread at one side of the loop over the

beveled upper edge of the bobbin case, the thread at the opposite side of the loop passing under the lower edge of the bobbin case, the thread moving through the space K between member 31 and bottom of the bobbin case, until the loop moves from the position shown at C in Fig. 5 of the drawings, to the position g, whereupon the tensioning means or arm 56, operates to draw the thread taut, causing the thread to slide over the edge of the bobbin case and loop around the bobbin 10 thread B, forming the stitch. This operation is repeated in forming a line of stitching as in sewing.

What is claimed is:

In a sewing machine, a body portion, a power 15 shaft within the body portion, a reciprocatory needle within the body portion operatively con-

nected with said shaft, underthread mechanism supported by said body portion and including a circular bobbin case having an annular groove formed in the periphery thereof, a disk-like member disposed under the bobbin case, the edge of the disk-like member being turned upwardly and inwardly, providing a flange disposed within said annular groove and connecting the disk-like member and bobbin case, a portion of the edge of the disk-like member being cut away providing hooks disposed in opposite directions, at the ends of the cut-away portion, means operative by said shaft for oscillating the disk-like member whereby said hooks are alternately engageable with a needle thread loop delivered below the bobbin case by said needle in forming a stitch.

CHARLES F. GOFORTH.
